BINDER

Matthew C. Klein, Milwaukee, Wis.

Application November 23, 1932, Serial No. 643,954

18 Claims. (Cl. 129—41)

This invention relates to an improvement in binders designed for use with loose leaves and also with catalogs, bulletins, pamphlets, or other material. The binder provides a simple, compact, 5 easily handled, and effective enclosure for the material contained therein and yet such material is accessible for full and complete as well as easy and convenient inspection at all times. Further, the leaves or other material may be readily placed 10 in or removed from the binder.

One of the objects of the invention is to provide a binder whose capacity for containing and holding sheets, catalogs, bulletins, or other papers, may be quickly and easily varied. Where loose 15 leaves are secured in the binder they are effectively and securely clamped in position and this notwithstanding that the number of such leaves may be widely varied. Catalogs, bulletins, or the like, contained in the binder are instantly available 20 for complete and convenient inspection. Along with these advantages the binder is so constructed as to be susceptible of convenient and economical manufacture and its parts are so constituted and organized as to relieve any of them of undue or 25 destructive strains with the result that the life of the binder is prolonged and its operation under the conditions of actual use is maintained satisfactory throughout its life.

The present application is a continuation in 30 part of and a substitute for my application for improvement in binders filed May 24, 1932, Serial No. 613,222.

Other objects and advantages reside in certain 35 novel features of the construction, arrangement and combination of parts which will be herein-after more fully described and particularly pointed out in the appended claims, reference being had to the accompanying drawings forming a part of this specification, and in which:

40 Figure 1 is a view partly in end elevation and partly in transverse vertical section showing a binder embodying the present invention employed for containing both loose leaves and other papers such as catalogs, pamphlets, bulletins, or the like;

45 Figure 2 is a view similar to Figure 1 but showing the binder open to render one of the bulletins or pamphlets available for inspection;

50 Figure 3 is a perspective view showing the general construction of a binder embodying the invention, the binder being opened up and parts being broken away for the sake of illustration;

55 Figure 4 is a detail view partly in elevation and partly in vertical section showing one of the locks or clamps employed for securing one of the

loose leaf clamping bars in position on the bands connecting the cover members of the binder;

Figure 5 is a view taken in section on line 5—5 of Figure 4;

Figure 6 is a view in section taken on line 6—6 of Figure 3 and illustrating one of the leaf clamping strips and the manner of connecting it to one of the cover members;

Figure 7 is a view similar to Figure 3 but showing a modified construction;

Figure 8 is a detail sectional view on line 8—8 of Figure 7; and

Figure 9 is a perspective view illustrating one of the leaf clamping strips employed with the binder shown in Figure 7.

Referring to the drawings, and more particularly to Figures 1 to 6, inclusive, it will be seen that the binder illustrated in this embodiment of the invention comprises a pair of cover members designated at 1 and 2. Except as will be pointed out hereinafter, the cover members 1 and 2 may be of any suitable construction and as usual consists of one or more plies of cardboard and a suitable covering material such as leather or the like. Integral with the covering material of the cover member 1 is a flexible backing 3 provided with a tapering or somewhat reduced extension 4. The cover member 2 has a pocket 5 therein opening throughout practically the entire extent of its rear edge but closed at the forward edge of the cover member except for a narrow slot-like aperture 6. A reinforcing metal strip 7 is suitably secured to the free edge of the extension 4 of the flexible backing. Any suitable means may be employed for appropriately securing this reinforcing strip to the extension 4 and in the construction illustrated eyelets or rivets designated at 8 are contemplated. A strap 9 is provided and has one end riveted or otherwise suitably connected as indicated at 10 to the extension 4 and also to the central portion of the reinforcing strip 7. This strap is extended through the pocket 5 and out through the slot-like aperture 6 thereof. When not employed for adjusting the extension 4, and consequently also the flexible backing of the binder, its loose end may be confined under a spring clasp 11.

The binder is equipped with any desired number of leaf holding bands designated at 12. In the embodiment shown in Figures 1 to 6, two such bands are provided. Each band has one end fastened as by means of an eyelet 13 to the reinforcing strip 7 and to the extension 4 of the flexible backing 3. Each band 12 is extended from its point of attachment to the strip 7 and ex-

tension 4 rearwardly through the pocket 5 and thence out through registering openings or slots designated at 14 and 15 provided respectively in the cover member 2 and in the flat attaching portion 16 of a sleeve-like roll or bead 17.

The end of each band opposite to that fastened to the strip 7 is bent back upon itself as indicated at 18 and into the formation of a hinge collar 20. The end portion 18 is suitably secured as by means of an eyelet or rivet to the part of the band which it engages. The hinge collars 20 at the ends of the bands are releasably and pivotally interfitted with the cover member 1, this being effected by positioning the attaching collars 20 in notches 21 formed in a hinge sleeve 22 and inserting a retaining pin 23 through the hinge sleeve and through the attaching collars. The hinge sleeve 22 has integral therewith an attaching strip or plate 24 which rests flatly against the inner edge portion of the cover and is riveted or secured thereto by eyelets or in any other suitable fashion. One end of the elongated retaining pin 23 is bent at an angle as indicated at 25 to provide a handle whereby to facilitate its insertion and removal.

The leaf holding bands 12 are constructed of spring steel or other resilient metal and when organized with the binder structure in the manner herein described are highly effective to engage notches formed in leaves, catalogs, or other papers, and extending out through the edges thereof for appropriately securing such papers in the binder and yet are also effective to allow of convenient and complete and full display of or access to the catalogs, pamphlets, leaves, or the like.

For the purpose of clamping loose leaves securely within the binder and in proper relation to said leaf holding band and to the other elements thereof cooperable leaf clamping bars 30 and 31 are provided and have openings 32 therein through which the leaf holding bands 12 freely extend. The leaf clamping bar 30 has bearing strips 33 riveted or otherwise suitably secured thereto adjacent its ends and pivotally receiving portions of the elongated retaining pins 23 projecting beyond the hinge sleeve 33 so that this leaf clamping bar 30 is pivotally interconnected with the cover member 1. The other leaf clamping bar 31 is freely slidable along the leaf holding bands 12 but may be securely fastened thereto in any adjustment by means of locking devices 35 mounted on the leaf clamping bar 31 and cooperable with the bands 12. There is one such locking device 35 for each leaf holding band.

Referring now to Figures 4 and 5 it will be seen that the locking devices have a common mounting strip 36 riveted or otherwise suitably secured as at 37 to the leaf clamping bar 31. Adjacent each leaf holding band 12 a stud 38 is threaded into the mounting strip 36. A clamping lever 39 has an opening 40 loosely receiving the stud 38 but the head of the stud provides a fulcrum engageable with the margins of the upper portion of the opening 40 and on which the clamping lever 39 is rockable. The band engaging portion of each clamping lever is designated at 41. The opposite end portion of each of these levers is formed on its underside with a semi-circular notch 42. Rotatable in this notch 42 is a semi-cylindrical camming member 43 formed as an integral lateral projection of a finger piece 44. Adjacent its notch 42 each lever 39 is cut away to provide clearance in which the finger piece 44

may operate. When the finger pieces 44 are pressed down to the full line position shown in Figure 4, the camming member 43 is rocking around to the position shown, thereby raising the adjacent end of the lever 39, rocking the lever about its fulcrum provided by the head of the stud 38, and causing the portion 41 thereof to have clamping frictional or securing engagement with the band 12 which is then confined between such portion 41 and the opposed portion of the strip 36. Swinging of the finger piece 44 from the full line position of Figure 4 to the dotted line position thereof brings the flat side of the camming member 43 adjacent the strip 36 and allows the camming member to be accommodated within the notch 42 throughout its extent. This allows the end 41 of the lever to move away from the band 12 thereby disconnecting the leaf clamping bar 31 from the bands and allowing free adjustment of the same along the bands 12.

In Figures 1 and 2 the loose leaves are designated at L and are shown as having notches N extending out through the inner edges thereof and through which the leaf holding bands 12 extend. The leaf clamping bar 30 engages one side of the leaves L whereas the opposite side is engaged by the clamping bar 31, the two clamping bars 30 and 31 cooperating to firmly clamp the notched ends of the leaves in position on the bands 12. The clamping bar 31 is held in position to effect this clamping of the leaves by virtue of the action of the locking devices 35 which clamp or lock the bar 31 to the bands 12 in the proper position.

The cover members may be adjusted toward and away from each other to provide the desired amount of flexible backing 3 between them by releasing the strap 9 from its clasp 11 and pulling the cover member 2 out along the extension 4 of the backing 3. In this way space may be provided on the bands 12 between the clamping bar 31 and the cover member 2 to allow of the engagement of catalogs, bulletins or pamphlets with the leaf holding bands 12 and provide for their proper retention within the binder. Such bulletins or the like may be readily displayed by opening up the binder as shown in Figure 2 and then opening up the bulletins. The extension of the bands 12 over the roll 17 causes them to bow or flex upwardly and this aids in the proper display of the pamphlets, bulletins, or the like.

To close the binder the strap 9 is pulled to draw the flexible backing taut and to cause the clamping bar 31 and the locking devices 35 of the clamping bar 31 to compress the inner edges of the catalogs, pamphlets, or the like, between bar 31 and the roll or bead 17, the cover members 1 and 2 being disposed in parallelism as shown in Figure 1. The provision of the roll 60 or bead 17 and of the hinge roll 22 together with the pivotal interconnection between the bands 12 and the hinge roll 22 precludes excessive or sharp bending of the leaf holding bands. The binder may be opened to afford access to or inspection of the loose leaves, catalogs or pamphlets by releasing the strap 9, swinging the cover members to open position, and allowing the leaf holding bands to flex or bow upwardly as shown in Figure 2.

The form of the invention shown in Figures 6, 7 and 8 is, in most respects, identical with that just described in that it has the cover members 1 and 2, the flexible backing 3 with its extension 4, the reinforcing strip 7, strap 9, clasp 11,

holding bands 12, sleeve-like rolls 17 and 22 with which the bands 12 are organized in the manner previously described, and leaf clamping bars 30 and 31. In fact, the only difference between this 5 form of the invention and that previously described, resides in the manner of adjustably securing the leaf clamping bar 31 in position. In lieu of the locking devices 35, a third band 50 is provided and has one end connected to the central 10 portion of the clamping bar 31 and its other end adjustably secured by a suitable fastening device 51 to the cover member 1, the intermediate portion of the third band 50 passing through a slot 52 in the leaf clamping bar 30. While 15 the particular manner of fastening one end of the band 50 to the bar 31 may be varied, preferably the band has at one end an eye or hinge collar 53 which pivotally and releasably embraces or receives an elongated securing pin 54, the pin 20 passing through strap-like bearings 55 secured to the bar 31 and projecting from one face thereof. The fastening device 51 may also take a variety of forms but in the particular construction illustrated consists of a guide 58 suitably 25 fastened to the attaching portion 24 of the hinge roll 22 and a set screw 56. The band 50 passes through the guide freely but may be held in position by tightening up on the set screw 56 to cause the screw to engage the band and clamp said band between itself and the attaching portion 24. A finger ring 57 may be secured to the free end of the band 50 to facilitate manipulation thereof.

In this form of the invention the action of the clamping bars 30 and 31 in holding the 30 leaves is regulated by the third band 50. Obviously, by releasing the set screw and moving the band 50 in one direction or the other the bar 31 can be moved to have clamping engagement with the leaves or to release them. When 40 the band 50 is pulled to cause the bar 31 to have clamping engagement with the leaves such clamping action may be maintained by tightening up on the set screw 56.

While I have shown and described several constructions as typical of the manner in which the invention may be embodied, it is to be understood that these constructions have been selected merely for the purpose of illustration and various changes in the size, form and arrangement of 45 the parts may be made without departing from the spirit of the invention or the scope of the subjoined claims.

The invention claimed is:

1. A binder comprising a pair of cover members, leaf holding bands extending therebetween, a pair of leaf clamping bars associated with said bands, one of said bars being connected to one of said cover members and the other of said bars being adjustable along said bands, means for releasably securing said adjustable bar in adjusted position, and means carried by said cover members and cooperable with said bands for preventing excessive flexure thereof.

2. A binder comprising a pair of cover members, leaf holding bands extending therebetween, a pair of leaf clamping bars associated with said bands, one of said bars being connected to one of said cover members and the other of said bars being adjustable along said bands, means for releasably securing said adjustable bar in adjusted position, and a bead or roll structure extending along the inner edge of at least one of said cover members and cooperable with said bands for preventing excessive flexure thereof.

3. A binder comprising a pair of cover mem-

bers, leaf holding bands extending therebetween, a pair of leaf clamping bars associated with said bands, one of said bars being connected to one of said cover members and the other of said bars being adjustable along said bands, means for releasably securing said adjustable bar in adjusted position and comprising an additional leaf holding band connected to said adjustable bar and freely shiftable relative to the other of said bars, and releasable means on one of said cover members for securing said additional band in adjusted position.

4. A binder comprising a pair of cover members, a plurality of resilient leaf holding bands extending between said cover members, means for pivotally connecting said bands at one end to one of said cover members, said other cover member having a pocket in which the other ends of said bands are slidable, means for pulling the bands into or allowing them to be pulled out of said pocket, and a roll formation on said cover member having the pocket and adjacent the points where the bands enter the pocket to insure proper flexion of the bands.

5. A binder comprising a pair of cover members, a plurality of leaf holding bands extending therebetween, means for clamping loose leaves in position on said bands, and means carried by one of said cover members and cooperable with said clamping means for aiding in holding catalogs, bulletins, pamphlets and the like on said bands separately from aforesaid loose leaves.

6. A binder comprising a pair of cover members, one of which has a pocket therein, a flexible backing connected to one of said cover members and having an extension adjustable in the pocket of the other to vary the extent of the flexible backing between said cover members, means for adjusting said extension, a number of leaf holding bands, each of which has one end secured to said extension and slidable therewith in the pocket of the one of said cover members and has its other end connected to said other cover member, a pair of leaf clamping bars, one of which is connected to one of said cover members and the other of which is adjustable along said bands, and means for releasably securing the bar slidable along said bands in adjusted position.

7. A binder comprising a pair of cover members, one of which has a pocket therein, a flexible backing connected to one of said cover members and having an extension adjustable in the pocket of the other to vary the extent of the flexible backing between said cover members, means for adjusting said extension, a number of leaf holding bands, each of which has one end secured to said extension and slidable therewith in the pocket of the one of said cover members and has its other end connected to said other cover member, a pair of leaf clamping bars, one of which is connected to one of said cover members and the other of which is adjustable along said bands, and means carried by said adjustable clamping bar and coacting with at least one of said bands for releasably securing said adjustable clamping bar in adjusted position.

8. A binder comprising a pair of cover members, a number of leaf holding bands extending between said cover member and interengaged therewith, a pair of leaf clamping bars, one of which is connected to one of said cover members and the other of which is adjustable along said bands, means carried by said adjustable bar and coacting with at least one of said bands for releasably securing said adjustable bar in adjusted position.

- position and comprising a pair of clamping members embracing one of said bands, at least one of said clamping members being fulcrumed on said adjustable bar for rocking movement 5 toward and away from the other clamping member, means for rocking said clamping member and holding it in clamping position, comprising a finger piece operated cam interposed between the clamping members for causing them to engage 10 and disengage said band.
10. A binder comprising a pair of cover members, one of which has a pocket therein, a flexible backing connected to one of said cover members and having an extension adjustable in the pocket of the other to vary the extent of the flexible backing between said cover members, means for adjusting said extension a number of leaf holding bands, each of which has one end secured to said extension and slideable therewith and has its other 15 end connected to said other cover member, a pair of leaf clamping bars, one of which is connected to one of said cover members and the other of which is adjustable along said bands, an additional band connected to said adjustable bar, the other of said bars having a slot through which 20 said additional band passes, and means mounted on one of the cover members and coacting with said additional band for releasably securing it in adjusted position.
30. 10. A binder comprising a pair of cover members, a flexible backing connecting said cover members, leaf holding bands extending between said cover members, and a pair of leaf clamping bars, one of which is pivotally connected with one of said cover members and the other of which is slideable along the leaf holding bands, and means for releasably securing said adjustable bar in adjusted position, said adjustable bar being positionable on said bands in spaced relation 35 to both of said cover members whereby said binder may be utilized for holding loose leaves and also bulletins, catalogs, pamphlets, and the like.
40. 11. A binder comprising a pair of cover members, a flexible backing connecting said cover members, leaf holding bands extending between said cover members, and a pair of leaf clamping bars, one of which is pivotally connected with one of said cover members and the other of which is slideable along the leaf holding bands, means for 45 releasably securing said adjustable bar in adjusted position, and means for causing said bands to flex outwardly when said cover members are opened up.
50. 12. A binder comprising a pair of cover members, a leaf clamping bar pivotally connected to one cover, leaf holding bands extending through said leaf clamping bar and pivotally connected on one end to said cover on the same axis as 55 said leaf clamping bar, the other end terminating in the other cover, and a second leaf clamping bar adjustably securable to said bands.
60. 13. A binder comprising a pair of cover members, one of which has a pocket therein, a flexible 65 backing connected to one of said cover members and having an extension adjustable in the pocket of the other to vary the extent of the flexible backing between said cover members, means for adjusting said extension, a number of leaf hold-
- ing bands extending between the cover members inwardly of the flexible backing, a pair of leaf clamping bars, one of which is pivotally connected to one of said cover members and the other of which is adjustable along said bands, said leaf clamping bars being located within the confines of the flexible backing and being disposed between the cover members in the closed position of the binder, and means for releasably securing the adjustable bar to said bands. 10
14. An expansion binder comprising a pair of cover members, a plurality of resilient metal strips bridging the rear edge portions of said cover members and adapted to receive loose leaf elements thereon, and metal plates secured along 15 the inner faces of the rear edge portions of said cover members and each having a bead extending longitudinally thereof, said beads forming rounded bearing surfaces receiving the loose leaf elements between them, the ends of said metal strips 20 having eyes, and pintle means in one of said beads passing through said eyes, the other plate having apertures slidably receiving said strips therethrough and deflecting said strips angularly out of the plane of the corresponding cover member, the 25 cover member carrying said last-named plate slidably receiving the other ends of said strips.
15. An expansion binder comprising a pair of cover members, a plurality of strips of resilient metal bridging the rear edge portions of said cover 30 members and adapted to receive loose leaf elements thereon, and means for detachably securing end portions of said strips to one of said cover members, the other cover member slidably receiving the other end portions of said strips and 35 having apertures through which said strips slidably pass and abutment means deflecting the exposed portions of the strips angularly out of the plane of the aperture cover member.
16. A binder comprising a pair of cover mem- 40 bers, resilient metal strips bridging the rear edge portions of said cover members and adapted to receive apertured loose leaf elements thereon, said resilient metal strips having curled end portions forming eyes and having sufficient stiffness 45 to maintain the configuration of said eyes, and pintle means for pivotally mounting said eyes to one of said cover members.
17. A binder comprising a pair of cover members, resilient metal strips bridging the rear edge 50 portions of said cover means and adapted to receive apertured loose leaf elements thereon, and means for pivotally and detachably mounting end portions of the strips on one of the cover members, said strips when detached at said end portions being supported by the other cover member in angular relation thereto and having sufficient 55 stiffness to form stems angularly projecting from said cover member to facilitate the threading thereon of said loose leaf elements. 60
18. A binder comprising a pair of cover members, resilient metal strips bridging the rear edge portions of said cover members and adapted to receive apertured loose leaf elements thereon, said strips having eyed end portions, and shiftable 65 pintle means for pivotally and detachably mounting the eyed end portions of the strips on one of said cover members.

MATTHEW C. KLEIN.
